UNITED STATES PATENT OFFICE.

HERBERT A. WALLACE, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

1,344,070.

Specification of Letters Patent. Patented June 22, 1920.

Application filed January 18, 1918. Serial No. 212,382.

To all whom it may concern:

Be it known that I, HERBERT A. WALLACE, a citizen of the United States, residing at Pittsburgh, in the county of Allegheny and State of Pennsylvania, have invented certain new and useful Improvements in Railway Signaling Systems, of which the following is a specification.

My invention relates to railway signaling systems, and particularly to systems of the type known as "normal danger signaling systems." That is, it aims to provide a novel and useful system of the type wherein the signals normally indicate "danger" ("stop"), and are changed to indicate "caution" and "proceed" only when a train is approaching.

I will describe one form of system embodying my invention, and will then point out the novel features thereof in claims.

The accompanying drawing is a diagrammatic view showing one form of signaling system embodying my invention.

Referring to the drawing, the reference character 1 designates the track rails of a railway over which traffic moves in the direction indicated by the arrow, which rails are divided by insulated joints 2 into a plurality of block sections A—B, B—C, C—D, etc. At the entrance end of each section is a signal which is designated by the reference character S with an exponent corresponding to the location of the signal. Each of these signals is adapted to give three indications, viz., "stop," "caution" and "proceed;" as here shown, each signal is of the three-position semaphore type, although any suitable type of signal capable of giving the three said indications may be substituted.

Each block section is provided with a track circuit comprising the rails of the section, a source of signaling current connected with the rails adjacent the exit end of the section, and a track relay having a winding connected with the rails adjacent the entrance end of the section. The immediate source of current for each section is a transformer designated U with an exponent corresponding to the location, the secondary winding of which is connected with the track rails through a pole-changer P operated by the signal for the section next in advance. These pole-changers are so operated that current from each source flows in the rails at a given instant in one direc-

tion, which I will term the "normal" direction, when the signal indicates "stop," and in the other or "reverse" direction when the signal indicates "caution" and "proceed." The end terminals of the primary winding of each transformer U receive current from a source of signaling current. As here shown, this current, for convenience, is taken from the secondary winding of a transformer which is designated T with an exponent corresponding to the location. The primary winding of each transformer T is supplied with alternating signaling current from a suitable source which is omitted from the drawing for the sake of simplification. Each track relay is designated R with an exponent corresponding to the location, and comprises a winding 3 connected with the track rails, and another winding 4 connected with terminal 5 of the primary winding of the adjacent transformer U and with a tap 6 at the middle point of this primary winding. Each relay comprises contact fingers 8, 9, 10 and 11, which contact fingers assume vertical positions when the relay is deenergized, but are swung to the right when the relay is energized in "normal" direction (due to current of normal polarity being supplied to the track circuit) and to the left when the relay is energized in "reverse" direction (due to current of reverse polarity being supplied to the track circuit).

At each signal location I provide an auxiliary relay designated by the reference character X, with an exponent corresponding to the location. Each of these relays comprises two windings 12 and 13, the winding 12 being constantly connected with the secondary of the adjacent transformer T. Winding 13 of each relay X is provided with a circuit which is controlled by contact 9 of the track relay at the next signal location in the rear; this circuit for winding 13 of relay X^B is from the left-hand terminal 5 of transformer U^A, through wire 15, resistance 15^a, contact finger 9 of relay R^A, wires 16 and 17, contact finger 8 of relay R^B, wire 18, winding 13 of relay X^B, wires 19, 20, 0, and 21, to the middle terminal 6 of transformer U^A. It follows then, that when relay R^A is deenergized and relay R^B is energized in either direction, winding 13 of relay X^B is supplied with current from the left-hand half of the primary of trans-

former U^A . Relay X^B is then energized in such direction that its contact fingers 22 and 23 are swung to the left, and this direction of energization of relay X^B I will call 5 the normal direction. Winding 13 of each relay X is provided with another circuit which is closed when the relay X at the next location in the rear is energized in normal direction. That is, this circuit is controlled 10 by contact finger 22 of the auxiliary relay at the next signal location in the rear. This circuit for winding 13 of relay X^B is from the right-hand terminal 7 of transformer U^A , through wire 24, resistance 25, contact finger 22 of relay X^A , wire 26, wire 17, contact finger 8 of relay R^B , wire 18, winding 13 of relay X^B , and wires 19, 20, 0 and 21 to the middle terminal 6 of the primary of transformer U^A . When this circuit is closed, 15 therefore, winding 13 of relay X^B is energized from the right-hand half of the primary of transformer U^A , so that relay X^B is energized in such direction that its contact fingers 22 and 23 are swung to the right, which direction I will term the 20 reverse direction of energization. It will be noted that when any one of the relays X is energized in the normal direction, contact 22 of such relay is closed, but that when the 25 relay is energized in the reverse direction this contact 22 is opened. Contact 22 is, of course, open when the relay is deenergized. Contact 23 is open when the relay is deenergized, and is closed when the relay is energized in either direction.

Each signal S is provided with a caution indication circuit and a proceed indication circuit, which circuits are controlled by the adjacent relays R and X . For example, the 40 caution indication circuit for signal S^B is from the left-hand terminal of the secondary of transformer T^B , through wires 27, 28 and 29, contact 23 of relay X^B , wire 30, right-hand point of contact 11 of relay R^B , wire 31, mechanism of signal S^B , wire 32, right-hand point of contact 10 of relay R^B , wires 33 and 34 to the right-hand terminal of transformer T^B . This circuit is 45 closed when relay R^B is energized in normal direction and relay X^B is energized in either direction. The proceed indication circuit for signal S^B is from the left-hand terminal of transformer T^B , through wires 27, 28 and 29, contact 23 of relay X^B , wire 30, left-hand 50 point of contact 11 of relay R^B , wire 35, mechanism of signal S^B , wire 32, left-hand point of contact 10 of relay R^B , and wires 33 and 34 to the right-hand terminal of secondary of transformer T^B . It will be noted 55 that this proceed indication circuit is closed when relay R^B is energized in the reverse direction and relay X^B is energized in either direction.

It follows then, that in order that either 60 circuit for a signal may be closed, the ad-

jacent relay X must be energized, and that the signal then will indicate "caution" or "proceed" according as the adjacent track relay is energized in normal or reverse direction.

The operation of the system is as follows:

When no trains are present, each relay X is deenergized, because the circuits for windings 13 of these relays are open, consequently, each signal indicates "stop." 70 Each track relay R is, therefore, energized in normal direction. This is the condition of the system as shown in the drawing.

I will now assume that a train moving in the direction indicated by the arrow enters 80 block section A—B. Relay R^A immediately becomes deenergized, so that contact 9 of this relay closes the normal energization circuit for winding 13 of relay X^B , whereupon the latter relay becomes energized in normal direction. The closure of the contact 23 of relay X^B closes the caution indication circuit for signal S^B , whereupon this signal moves to the caution position. The closure of contact 22 of relay X^B closes the reverse energization circuit for winding 13 of relay X^C , whereupon the latter relay becomes energized in reverse direction, so that its contacts are swung to the right. The closure 90 of contact 23 of relay X^C closes the caution indication circuit for signal S^C , whereupon this signal moves to the caution position. When signal S^C reaches the caution position, or just before it reaches this point, pole-changer P^C is reversed so that relay R^B becomes energized in the reverse direction. The contacts of this relay then swing to the left, 100 so that contact 11 closes the proceed indication circuit of signal S^B . Signal S^B then moves to the proceed position. During the 105 reversal of relay R^B , contact 9 of this relay momentarily closes the normal energization circuit for winding 13 of relay X^C , so that momentarily the winding 13 of relay X^C is deenergized. The moving parts of this relay or of signal S^C , or both, are so designed, 110 however, that during this interval the pole-changer P^C is not operated to change the track circuit for section B—C back to normal polarity.

It will be noted that contact 22 of relay X^C remains open, so that relay X^D remains deenergized; signal S^D , therefore, continues to occupy the stop position.

The operation of the system as the train 120 passes from section A—B into section B—C, and so on along the stretch of track, will be apparent from the foregoing.

Although I have herein shown and described only one form of railway signaling 125 system embodying my invention, it is understood that various changes and modifications may be made therein within the scope of the appended claims without departing from the spirit and scope of my invention. 130

Having thus described my invention, what I claim is:

1. A normal danger signaling system comprising a plurality of block sections, a signal for each section adapted to indicate proceed, caution and stop, a track circuit for each section including a source of current and a relay responsive to reversals of current, means controlled by each signal for connecting the source of current for the section in the rear with the rails of the section in normal direction when the signal indicates stop and in reverse direction when the signal indicates caution or proceed, an auxiliary relay for each section responsive to reversals of current, means controlled by each track relay for energizing the auxiliary relay for the section in advance in normal direction when the track relay is deenergized, means controlled by each auxiliary relay when energized in normal direction for energizing the auxiliary relay for the section in advance in reverse direction, a caution indication circuit for each signal closed when the auxiliary relay for the same section is energized in either direction and the track relay for the same section is energized in normal direction, and a proceed indication circuit for each signal closed when the auxiliary relay for the same section is energized in either direction and the track relay for the same section is energized in reverse direction. 70
2. A normal danger signaling system comprising a plurality of block sections, a signal for each section adapted to indicate proceed, caution and stop, a track circuit for each section including a source of current and a relay responsive to reversals of current, means controlled by each signal for connecting the source of current for the section in the rear with the rails of the section in normal direction when the signal indicates stop and in reverse direction when the signal indicates caution, an auxiliary relay for each section responsive to reversals of current, one terminal of each auxiliary relay being connected with the middle point of a source of current, means controlled by each track relay when deenergized for connecting the remaining terminal of the auxiliary relay for the section in advance with one terminal of the source for such relay whereby such auxiliary relay is then energized in normal direction, means controlled by each auxiliary relay when energized in normal direction for connecting the said remaining terminal of the auxiliary relay for the section in advance with the other terminal of the source for such latter relay whereby the latter relay is then energized in reverse direction, a caution indication circuit for each signal closed when the auxiliary relay for the same section is energized in either direction and the track 10 15 20 25 30 35 40 45 50 55 60 65 70 75 80 85 90 95 100 105 110 115 120 125
- relay for the same section is energized in normal direction, and a proceed indication circuit for each signal closed when the auxiliary relay for the same section is energized in either direction and the track relay for the same section is energized in reverse direction. 70
3. A normal danger signaling system comprising a plurality of block sections, a track relay for each section responsive to reversals of current, means for supplying current to the rails of each section in one direction or the other, an auxiliary relay for each section responsive to reversals of current, means controlled by each track relay for energizing the auxiliary relay for the section in advance in one direction and means controlled by each auxiliary relay when energized in such direction for energizing the auxiliary relay for the next section in advance in the other direction and signals for the sections controlled by said track relays and by said auxiliary relays. 85
4. A normal danger signaling system comprising a plurality of block sections, a track relay for each section responsive to reversals of current, an auxiliary relay for each section also responsive to reversals of current, means controlled by each track relay for energizing the auxiliary relay for the section in advance in one direction, and means controlled by each auxiliary relay when energized in such direction for energizing the auxiliary relay for the section next in advance in the other direction, a signal for each section controlled by the track relay and by the auxiliary relay for such section, and means controlled by each signal for supplying current to the rails of the track section in the rear in one direction or the other. 95
5. A normal danger signaling system comprising a plurality of block sections, a track relay for each section responsive to reversals of current, means for supplying current to the rails of each section in one direction or the other, an auxiliary relay for each section responsive to reversals of current, means controlled by said track relays and by the auxiliary relays for energizing the auxiliary relay for the section next in advance of an occupied section in one direction and for energizing the auxiliary relay for the second section in advance of an occupied section in the other direction, and signals for the block sections controlled by said track relays and by said auxiliary relays. 110 115 120

In testimony whereof I affix my signature in presence of two witnesses.
